Primary Examiner — Jennifer Rivard*Assistant Examiner* — Alison M Ofstun(74) *Attorney, Agent, or Firm* — Lawrence Cruz, Esq.; Ryan, Mason & Lewis, LLP(57) **CLAIM**

The ornamental design for a hair parting tool, as shown and described.

DESCRIPTION

FIG. 1 is a first perspective view of the hair parting tool showing my new design;

FIG. 2 is a rear perspective view thereof;

FIG. 3 is a first side elevation view thereof;

FIG. 4 is a second side elevation view thereof;

FIG. 5 is a top plan view thereof;

FIG. 6 is a bottom plan view thereof;

FIG. 7 is a front view thereof; and,

FIG. 8 is a rear view thereof.

In the drawings, the broken lines illustrate portions of the hair parting tool which form no part of the claimed design.
